UNITED STATES PATENT OFFICE.

LEBRECHT/STEINMÜLLER, OF GUMMERSBACH, GERMANY.

STEAM-GENERATOR.

1,054,248.

Specification of Letters Patent. Patented Feb. 25, 1913.

Application filed September 27, 1911. Serial No. 651,599.

To all whom it may concern:

Be it known that I, LEBRECHT STEINMÜLLER, a subject of the King of Prussia, and resident of Gummersbach, in the Province 5 of the Rhine, German Empire, have invented certain new and useful Improvements in Steam-Generators, of which the following is a specification.

This invention relates to certain improvements in steam generators and has for its object to provide means for regulating the temperature of saturated steam for supply to turbines and like machinery.

According to the present invention the 15 superheated steam is first caused to pass through an intermediate heater heated by the superheated steam so that the saturated steam from the boiler is dried and slightly superheated before passing to the superheater proper, where the steam is raised to a high 20 temperature and thereafter passed through the intermediate heater so as to give up part of its heat thereto, so that the superheated steam is supplied at a suitable temperature 25 to the turbine or the like. The intermediate heater enables water and foreign matter to be separated from the steam before the latter passes to the superheater so that damage to the superheater is obviated. The 30 intermediate heater can also be readily constructed so as to be accessible and thus easily controlled and cleaned. On the other hand no drawback is presented in superheating the steam in the superheater to a higher 35 temperature than is required for the turbine or the like, as the insertion of the intermediate heater protects the superheater from internal damaging influences.

In order that the invention may be more 40 clearly understood, reference is made to the accompanying drawings, in which:

Figure 1 is a side view, showing the intermediate heater in section, of the connections from the boiler to the superheater and the 45 connections therefrom to the turbine or the like to be driven. Fig. 2 is a diagrammatic view of a slightly modified form of Fig. 1. Fig. 3 is a detail view of the regulating valve shown in Fig. 2. Fig. 4 illustrates in 50 perspective a modified construction of regulating valve.

Referring to Fig. 1 of the drawings: 1 indicates a steam pipe leading from the boiler, said steam pipe opening into an intermediate 55 heater 2, which is inserted between the steam pipe 1 and a pipe 3 leading to the

superheater 4. Said superheater communicates with a pipe 5 which returns to the intermediate heater 2 and the steam after passing therethrough escapes by way of the pipe 6 to the turbine or the like. The intermediate heater 2 comprises a cylindrical chamber having removable end covers 7 to which are connected the steam pipes 1 and 3 respectively. Within the interior of the heater 2 are arranged two transverse plates 8 dividing the heater 2 into end chambers 9 and 10 and a central chamber 11, within which latter are arranged a series of horizontal tubes 12, beaded in the end plates 8 and open at each end to the chambers 9 and 10 respectively. It will thus be seen that steam enters the end chamber 9 of the heater 2 from the steam pipe 1 and passes therefrom through the tubes 12 into the end chamber 10 and 75 therefrom through the pipe 3 to the superheater 4. The steam passing through the tubes 12 is heated therein by superheated steam within the central chamber 11 of the heater 2, the steam entering the chamber 11 80 by way of the pipe 5 and after flowing around and between the tubes 12 passing out by way of the pipe 6. The steam pipe 1 is provided with a valve 13 whereby the supply of steam to the heater 2 may be cut off, 85 in which case the steam from the boiler may pass directly to the engine through a pipe 14 connecting the pipe 1 with the pipe 6. Instead of supplying steam directly to the 90 superheater 4 without passing through the heater 2, the steam in this case passing through a pipe 15 leading directly from the pipe 1 to the pipe 3, the valve 13 in the pipe 1 and the valve 36 in the pipe 14 being set 95 in the cut-off position. The steam from the superheater may also be supplied directly to the pipe 6 without passing through the heater 2 by way of a pipe 16. Means are also provided whereby steam from the pipe 100 1 may be caused to pass through the heater 2 into the pipe 3 and from thence through a branch pipe 17 directly to the pipe 5 without passing through the superheater and directly to the pipe 6 through a pipe 18. Inasmuch as the pressure in the heater 2 and on both sides of the partitions 8 is almost uniform, very thin tubes 12 and partitions 8 may be employed and thus the exchange of heat considerably facilitated. 105 The mode of operation is as follows:— When the valve 13 is open, steam from the

boiler enters by way of the pipe 1 at a temperature of say 180° C. and on passing through the tubes 12, is dried and slightly superheated. The slightly superheated steam then passes to the superheater 4 through the pipe 3 and returns to the heater 2 by way of the pipe 5 and passes between and around the tubes 12. During the passage of the superheated steam through the chamber 11 the superheated steam is somewhat cooled, the steam coming for example from the superheater 4 at a temperature of about 400° C. and being cooled to a temperature of about 350° C. before being supplied to the turbine or the like. If it is now desired to regulate the temperature of the superheated steam, part of the steam coming from the heater 2 may be caused to pass through the pipe 17 direct to the pipe 5, while the remainder of the steam passes directly to the superheater 4 or a part of the steam may be directly supplied to the turbine through a pipe 18. As the amount of steam now passing through the superheater 4 is diminished, a diminished heating of the saturated steam passing through the tubes 12 results, even although the steam passing through the superheater 4 may be raised to a higher temperature. It will also be readily understood that if steam from the pipe 1 is supplied directly to the superheater 4 by way of the pipe 15 without passing through the heater 2, the degree of superheating in the superheater will be diminished, thus regulating the temperature of the superheated steam supplied to the turbine by way of the pipe 6. It will also be understood that a part of the steam may be supplied directly to the superheater 4 while the remainder is passed through the heater 2. The temperature of the steam supplied to the pipe 6 may be increased by passing a part of the steam directly to the pipe 6 while the remainder is caused to pass through the chamber 11 of the heater 2.

In order to avoid excessive heating of the superheater tubes at the point where the superheated steam passes out of the superheater owing to the small cooling of the highly superheated steam, or in order to maintain the temperature of the steam on entering the superheater below a predetermined temperature, the amount of water in the steam entering the heater 2 may be increased in any desired manner. For example, water may be sprayed into the steam pipe 1 through a water pipe 32. The supply of water to the steam in this manner before the steam enters the superheater, has the advantage over the direct supply of water to the steam in the superheater, that all deposits can readily settle in accessible parts, viz. in the intermediate heater 2, while on the other hand the danger of water hammer effects in the engine cylinder and burning of

the superheater tubes owing to the deposit of foreign matter therein is obviated. Fig. 2 illustrates an apparatus whereby the temperature of the superheated steam may be automatically regulated. 19 illustrates a steam boiler of any suitable type while 20 indicates an outlet for wet steam and 21 an outlet for dry steam, the inlet end of the latter pipe being provided with a drying and filtering apparatus 22 of the usual type. Inserted between the pipe 20 and the superheater 4 is the intermediate heater 2 of the type described and illustrated in Fig. 1, so that the wet steam passing through the pipe 20 is dried and somewhat superheated in the heater 2 before passing to the superheater 4. The superheated steam leaves the superheater through a tube 5 and enters the intermediate heater 2 in the manner already described, the steam thereafter passing out through the steam supply pipe 6. The pipe 3 leading from the heater 2 and the dry steam pipe 21 leading from the boiler 19 are connected together by means of a valved connection 25 which communicates through a pipe 27 with the superheater 4. The valve 25 enables the amount of wet steam passing through the heater 2 and the amount of dry steam passing through the pipe 21 to be controlled. In the steam pipe 5 is arranged a thermostat 23 of any suitable type which is actuated by the variations in temperature of the steam passing through the pipe 5. Said thermostat is mechanically or otherwise connected with the regulating valve 25, the connection of the thermostat 23 with the valve 25 being illustrated in Fig. 2 by the dotted line 28. If desired an auxiliary thermostat 34 may also be inserted in the steam supply pipe 6, the latter being of course dependent upon the final temperature of the steam supplied to the turbine. It will of course be readily understood that if desired electrical thermostats or mechanical arrangements of any known type may be employed for this purpose.

The construction of the regulating valve 25 is shown in detail in Fig. 3 and comprises a substantially semi-cylindrical valve 25 rotatably arranged in a three-way valve casing 26 open at one side to the pipe 3 and at the other side to the pipe 21, the steam mixing in the valve casing 26 and passing therefrom through the pipe 27 to the superheater. It will be readily understood that by rotating the valve 25 in the one direction or the other the supply of wet or dry steam can be controlled as required so as to vary the humidity and temperature of the steam supplied to the superheater according to requirements.

The operation of the foregoing device is as follows:—The valve 25 is so arranged as to permit a certain quantity of steam from the heater 2 to pass to the superheater

4 and mix with a certain quantity of dry steam supplied by way of the pipe 21. The mixed steam is superheated in the superheater 4 and then passes through the pipe 5 and through the heater 2 where it gives up a part of its heat to the latter and thus slightly superheats the wet steam passing through the tubes of the heater 2, until it finally passes out through the pipe 6 at the desired temperature. If now the temperature of the superheated steam flowing through the pipe 5 and the thermostat 23 exceeds a predetermined amount, the regulating valve 24 is operated by the thermostat 23 so that more wet steam will be admitted to the superheater 2 while the supply of dry steam from the pipe 21 to the superheater 4 will be correspondingly diminished. It follows therefrom that the wet steam flowing through the heater 2 will absorb more heat from the superheated steam passing therethrough and the final temperature of the superheated steam will thus be decreased. If on the other hand the final temperature of the superheated steam is too low, the amount of wet steam passing through the heater 2 will be correspondingly diminished and the amount of dry steam passing to the superheater 4 correspondingly increased by rotating the valve 25 in the reverse direction. The thermostatic device 24 which may be used either alone or in conjunction with the thermostatic device 23 may be caused to actuate the regulating valve 25 in a similar manner thereto.

Fig. 4 illustrates a modified form of regulating valve, the pipes 3 and 21 in this case being shown as parallel to one another and each provided with butterfly valves 29 and 30 respectively mounted upon a rotatable shaft 31 and at right angles to one another so that when the one valve is closed, the other valve will be in its open position. The shaft 31 can be rotated in any known manner from the thermostatic devices 23 or 24 and its rotation will cause the valves 29 and 30 to open or close respectively as required.

I claim:—

1. In a steam generator, a heater for drying and heating steam from the boiler before passing it to a superheater, said heater being heated by the superheated steam coming from said heater and superheater, whereby said superheated steam is at the same time slightly cooled.

2. In a steam generator, a steam pipe leading from the boiler to a superheater, an intermediate heater in said pipe, a pipe connection supplying steam direct from the boiler to the superheater, a cut-off valve in said pipe connection, a superheated steam pipe leading from said superheater to said heater, which latter is adapted to be heated by the superheated steam, and a superheated steam supply pipe leading from said heater.

3. In a steam generator, a heater, a steam pipe leading from the boiler to said heater, a superheater, a connection between said heater and superheater, a return pipe from said superheater to said heater, which latter is adapted to be heated by the superheated steam, a superheated steam supply pipe leading from said heater, and a valved branch pipe connecting said connection with said return pipe.

4. In a steam generator, a heater, a steam pipe leading from the boiler to said heater, a superheater, a connection between said heater and superheater, a return pipe from said superheater to said heater, which latter is adapted to be heated by the superheated steam, a superheated steam supply pipe leading from said heater and a valved branch pipe connecting said connection with the superheated steam supply pipe.

5. In a steam generator, a heater, a steam pipe leading from the boiler to said heater, a superheater, a return pipe from said superheater to said heater, which latter is adapted to be heated by the superheated steam, a superheated steam supply pipe leading from said heater, a valved branch pipe connecting said connection with said return pipe, and a valved branch pipe connecting said connection with the superheated steam supply pipe.

6. In a steam generator, a heater, a steam pipe leading from the boiler to said heater, a superheater, a connection between said heater and superheater, a valved pipe supplying steam direct from the boiler to the superheater, a return pipe from said superheater to said heater, which latter is adapted to be heated by the superheated steam, a superheated steam supply pipe leading from said heater, and a valved branch pipe connecting said connection with said return pipe.

7. In a steam generator, a heater, a steam pipe leading from the boiler to said heater, a superheater, a connection between said heater and superheater, a valved pipe supplying steam direct from the boiler to the superheater, a return pipe from said superheater to said heater, which latter is adapted to be heated by the superheated steam, a superheated steam supply pipe leading from said heater, and a valved branch pipe connecting said connection with the superheated steam supply pipe.

8. In a steam generator, a heater, a steam pipe leading from the boiler to said heater, a superheater, a connection between said heater and superheater, a return pipe from said superheater to said heater, which latter is adapted to be heated by the superheated steam, a superheated steam supply pipe leading from said heater, a valved branch pipe connecting said connection with said return pipe, and a valved branch pipe

connecting said connection with the superheated steam supply pipe.

9. In a steam generator, a heater, a steam pipe leading from the boiler to said heater, a superheater, a connection between said heater and superheater, a return pipe from said superheater to said heater, which latter is adapted to be heated by the superheated steam, a superheated steam supply pipe 70 leading from said heater, and a valved pipe directly connecting said return pipe with the superheated steam supply pipe.

10. In a steam generator, a steam pipe leading from the boiler to a superheater, an intermediate heater in said pipe, a pipe connection supplying steam direct from the boiler to the superheater, a cut-off valve in said pipe connection, a superheated steam pipe leading from said superheater to said heater, which latter is adapted to be heated by the superheated steam, a superheated steam supply pipe leading from said heater, and a valved pipe directly connecting said return pipe with the superheated steam supply pipe.

11. In a steam generator, a heater, a steam pipe leading from the boiler to said heater, a superheater, a connection between said heater and superheater, a return pipe 30 from said superheater to said heater, which latter is adapted to be heated by the superheated steam, a superheated steam supply pipe leading from said heater, a valved branch pipe connecting said connection 35 with the superheated steam supply pipe, and a valved pipe directly connecting said return pipe with the superheated steam supply pipe.

12. In a steam generator, a heater, a steam pipe leading from the boiler to said heater, a superheater, a return pipe from said superheater to said heater, which latter is adapted to be heated by the superheated steam, a superheated steam supply pipe 45 leading from said heater, a valved branch pipe connecting said connection with said return pipe, a valved branch pipe connecting said connection with the superheated steam supply pipe and a valved pipe directly connecting said return pipe with the superheated steam supply pipe.

13. In a steam generator, a heater for drying and heating steam from the boiler before passing it to a superheater, said heater being heated by the superheated steam whereby the latter is at the same time slightly cooled, and means for supplying water to said steam before its entry into the heater.

14. In a steam generator, a heater, a wet steam pipe leading from the boiler to said heater, a superheater, a connection between said heater and superheater, a dry steam pipe leading directly from the boiler to the superheater, means for regulating the flow 65 of wet steam through said heater and for regulating the flow of dry steam through said dry steam pipe, a return pipe from said superheater to said heater, which latter is adapted to be heated by the superheated steam, a thermostatic device in said return pipe and adapted to operate said regulating means, and a superheated steam supply pipe leading from said heater.

15. In a steam generator, a heater, a wet steam pipe leading from the boiler to said heater, a superheater, a connection between said heater and superheater, a three-way valve casing in said connection, a dry steam pipe supplying dry steam directly from the boiler to said valve casing, a valve in said casing for proportionately regulating the steam flowing from said heater to the superheater and the dry steam flowing directly to said superheater, a return pipe from said superheater to said heater, which latter is adapted to be heated by the superheated steam, a thermostatic device in said return pipe and adapted to operate said valve, and a superheated steam supply pipe leading from said heater.

16. In a steam generator, a heater, a wet steam pipe leading from the boiler to said heater, a superheater, a connection between said heater and superheater, a dry steam pipe leading directly from the boiler to the superheater, means for regulating the flow of wet steam through said heater and for regulating the flow of dry steam through said dry steam pipe, a return pipe from said superheater to said heater, which latter is adapted to be heated by the superheated steam, a superheated steam supply pipe leading from said heater, and a thermostatic device in said superheated steam supply pipe and adapted to operate said regulating means.

17. In a steam generator, a heater, a wet steam pipe leading from the boiler to said heater, a superheater, a connection between said heater and superheater, a dry steam pipe leading directly from the boiler to the superheater, means for regulating the flow of wet steam through said heater and for regulating the flow of dry steam through said dry steam pipe, a return pipe from said superheater to said heater, which latter is adapted to be heated by the superheated steam, a superheated steam supply pipe leading from said heater, and a thermostatic device in said superheated steam supply pipe and adapted to operate said regulating means.

18. In a steam generator, a heater, a wet steam pipe leading from the boiler to said heater, a superheater, a connection between said heater and superheater, a three-way valve casing in said connection, a dry steam 130

- pipe supplying dry steam directly from the boiler to said valve casing, a valve in said casing for proportionately regulating the steam flowing from said heater to the superheater and the dry steam flowing directly to said superheater, a return pipe from said superheater to said heater, which latter is adapted to be heated by the superheated steam, a thermostatic device in said return pipe and adapted to operate said valve, a superheated steam supply pipe leading from said heater, and a thermostatic device in said superheated steam supply pipe also adapted to operate said valve.
19. In a steam generator, a heater comprising a chamber divided into two end compartments and a central compartment, tubes passing through said central compartment and opening into said end compartments, a steam pipe leading from the boiler to one of said end compartments, whereby the steam is caused to pass through said tubes into the other of said end compartments, a superheater, a connection from the latter of said end compartments to the superheater, a pipe connecting the superheater with said central compartment whereby superheated steam is caused to pass around and between said tubes, and a superheated steam supply pipe leading from said central compartment.
20. In a steam generator, a heater comprising a chamber divided into two end compartments and a central compartment, tubes passing through said central compartment and opening into said end compartments, a steam pipe leading from the boiler to one of said end compartments whereby the steam is caused to pass through said tubes into the other of said end compartments, a superheater, a connection from the latter of said end compartments to the superheater, a pipe connecting the superheater with said central compartment whereby superheated steam is caused to pass around and between said tubes, and a superheated steam supply pipe leading from said central compartment.
21. In a steam generator, a heater comprising a chamber divided into two end compartments and a central compartment, tubes passing through said central compartment and opening into said end compartments, a steam pipe leading from the boiler to one of said end compartments, whereby the steam is caused to pass through said tubes into the other of said end compartments, a superheater, a connection from the latter of said end compartments to the superheater, a pipe connecting the superheater with said central compartment whereby superheated steam is caused to pass around and between said tubes, a valved branch pipe connecting said connection with the pipe connecting the superheater with said central compartment, and a superheated steam supply pipe leading from said central compartment.
22. In a steam generator, a heater comprising a chamber divided into two end compartments and a central compartment, tubes passing through said central compartment and opening into said end compartments, a steam pipe leading from the boiler to one of said end compartments, whereby the steam is caused to pass through said tubes into the other of said end compartments, a superheater, a connection from the latter of said end compartments to the superheater, a pipe connecting the superheater with said central compartment whereby superheated steam is caused to pass around and between said tubes, a superheated steam supply pipe leading from said central compartment and a valved pipe connecting said connection with said superheated steam supply pipe.
23. In a steam generator, a heater comprising a chamber divided into two end compartments and a central compartment, tubes passing through said central compartment and opening into said end compartments, a steam pipe leading from the boiler to one of said end compartments, means for supplying water to the steam in said steam pipe, whereby wet steam is caused to pass through said tubes into the other of said end compartments, a superheater, a connection from the latter of said end compartments to the superheater, a pipe connecting the superheater with said central compartment whereby superheated steam is caused to pass around and between said tubes, and a superheated steam supply pipe leading from said central compartment.
24. In a steam generator, a heater comprising a chamber divided into two end compartments and a central compartment, tubes passing through said central compartment and opening into said end compartments, a steam pipe leading from the boiler to one of said end compartments, whereby the steam is caused to pass through said tubes into the other of the said end compartments, a superheater, a connection from the latter of said end compartments to the superheater, a dry steam pipe leading directly from the boiler to the superheater, means for regulating the flow of steam through said heater and for regulating the flow of dry steam through said dry steam pipe, a pipe connecting the superheater with said central compartment, whereby superheated steam is caused to pass around and between said tubes, a thermostatic device in said pipe connecting the superheater with said central compartment and adapted to operate said regulating means, and a superheated steam supply pipe leading from said central compartment.
25. In a steam generator, a heater comprising a chamber divided into two end compartments and a central compartment, tubes passing through said central compartment and opening into said end compartments, a steam pipe leading from the boiler to one of said end compartments, whereby the steam is caused to pass through said tubes into the other of the said end compartments, a superheater, a connection from the latter of said end compartments to the superheater, a dry steam pipe leading directly from the boiler to the superheater, means for regulating the flow of steam through said heater and for regulating the flow of dry steam through said dry steam pipe, a pipe connecting the superheater with said central compartment, whereby superheated steam is caused to pass around and between said tubes, a thermostatic device in said pipe connecting the superheater with said central compartment and adapted to operate said regulating means, and a superheated steam supply pipe leading from said central compartment.

compartments and a central compartment, tubes passing through said central compartment and opening into said end compartments, a steam pipe leading from the boiler to one of said end compartments, whereby the steam is caused to pass through said tubes into the other of the said end compartments, a superheater, a connection from the latter of said end compartments to the superheater, a dry steam pipe leading directly from the boiler to the superheater, means for regulating the flow of steam through said heater and for regulating the flow of dry steam through said dry steam pipe, a

pipe connecting the superheater with said central compartment, whereby superheated steam is caused to pass around and between said tubes, a superheated steam supply pipe leading from said central compartment, and a thermostatic device in said supply pipe and adapted to operate said regulating means. 15

In witness whereof I have hereunto set my hand in the presence of two witnesses.

LEBRECHT STEINMÜLLER.
